UNITED STATES PATENT OFFICE.

FERDINAND E. CANDA, OF NEW YORK, N. Y.

BALL-ROLLING MILL.

1,266,402.

Specification of Letters Patent. Patented May 14, 1918.

Application filed June 25, 1915. Serial No. 36,201.

To all whom it may concern:

Be it known that I, FERDINAND E. CANDA, a citizen of the United States of America, and a resident of New York, in the county 5 of New York and State of New York, have invented certain new and useful Improvements in Ball-Rolling Mills, of which the following is a specification.

My invention relates to improvements in ball rolling machines. The machine for that purpose herein illustrated and described carries out the method of ball rolling described and claimed in my application for Letters Patent filed February 23, 1915, Serial No. 15 9845, embodying compressing transversely at spaced intervals a bar of compressible material, and causing simultaneous rotation of such bar and gradual grooving of such bar at points of application of pressure, and 20 forcing the material, displaced by such rolling, outward between successive grooves; the result being a ball of larger diameter than the initial diameter of the bar from which the balls are formed. My invention consists 25 in novel coöperating and reciprocating ball forming means, and in other features, all as hereinafter described and particularly pointed out in the appended claim.

The machine herein described is particularly intended for forming balls of large 30 diameter, say from three inches upward, from steel or other metals heated to a forging or rolling temperature; but is also applicable to the forming of balls from lead 35 and like metals which may be rolled cold; also from non-metallic materials capable of being rolled.

The objects of my invention are, to improve means for forming balls and other 40 objects of rotation, not necessarily spherical, and to make such means simple, compact, durable, efficient, and of such nature that they may be operated by workmen acquainted with ordinary rolling operations.

45 I will now proceed to describe my invention with reference to the accompanying drawings, and will then point out the novel features in claim:

Figure 1 shows a vertical longitudinal section of a horizontal type of ball rolling machine embodying my invention; Fig. 1^a 50 shows a transverse vertical section through the rack bars and gear.

Fig. 2 shows a partial top view and partial horizontal section of the said machine.

Fig. 3 shows an end view of the machine.

Figs. 4, 5 and 6 are diagrammatic views, showing the ball forming dies in section, and in different stages of the operation of rolling blanks into balls. Fig. 7 is a similar 60 diagrammatic view on a smaller scale, showing means whereby two coöperating ball rolling dies may form a ball at each stroke of said dies.

Fig. 8 shows a side elevation of alternative 65 drive means for the dies.

Fig. 9 shows a fragmentary vertical longitudinal section of a ball rolling mill similar to that shown in Figs. 1, 2 and 3, but 70 embodying roller bearings for the reciprocating dies.

Fig. 10 shows a side elevation of a vertical ball rolling mill of the general type of the machine shown in Figs. 1, 2 and 3.

Fig. 11 is a fragmentary detail horizontal 75 section of a portion of the machine shown in Fig. 9, on section line y—y, looking upward.

Fig. 12 is a more or less diagrammatic elevation of coöperating ball forming dies and associated parts, indicating the use of structurally separate finishing dies. 80

Figs. 13 and 14 are fragmentary transverse sections of dies adapted for rolling non-spherical articles of rotation.

Referring first to Figs. 1-6 inclusive; 85 Numerals 1 and 2 designate, respectively, upper and lower grooved ball rolling dies, mounted upon sliding carriages 3 and 4, respectively, the grooves of the two dies registering, the carriages sliding on suitable guides provided on frame members 5 and 6. The carriages 3 and 4 are provided with rack bars 7 and 8 respectively and a gear 9 having a shaft 10 mounted in suitable 90 bearings in the frame of the machine, is provided for communicating motion from the one rack bar to the other. It will be seen that if either of these rack bars be caused to move longitudinally, a corresponding but opposite motion will be communicated 95 through the gear 9 to the other rack bar. Various means may be employed for so moving one of the rack bars and communicating motion, through the gear 9 to the other rack bar; I have illustrated for the 100 purpose hydraulic cylinders 11 having within them pistons 12 and piston rods 13 connected by a cross head 14 to each other and to the lower rack bar 8; but it is obviously immaterial to which of the rack bars the 110

cross head is connected. The hydraulic cylinders will be understood to be provided with the usual admission and exhaust ports, and valve gear controlling such ports, by 5 which the pistons can be caused to move in either direction at will. For convenient support of the cross head, a carrying wheel 15 is provided.

The ball rolling dies 1 and 2 are provided 10 with grooves 17, and intervening ribs 18, of such nature that, when the parts are in the position shown in Fig. 1, a rod 16, forming a ball-blank, may be introduced between the dies 1 and 2; and then, as these dies are 15 moved in opposite directions (the lower die moving toward the left of Fig. 1 and the upper die moving toward the right of that figure) the material of the rod will be forced outward into said grooves, the ridges between the grooves forming necks in the bar and, eventually, severing or nearly severing such necks; by which time the material of the bar forced into the grooves will have assumed substantially the cross section of the 20 grooves, and will have assumed a practically spherical shape. It will be understood that as the dies 1 and 2 move in opposite directions the ball blank rolls, and eventually drops off from the right hand end of the die 25 2 as a series of separate balls, or as a ball-bar consisting of a plurality of balls connected by small and narrow necks, according to the adjustment of the dies. The lower die, 2, is shown as mounted so as to be capable of 30 adjustment upon an inclined slide 19 whereby the distance of die 2 from die 1 may be varied at will. A lip 20 provided in connection with die 2, prevents the bar from rolling off the left hand end of that die 40 2 at the start of the operation.

Figs. 4, 5 and 6 show progressive stages in the rolling of the ball and indicate the gradual increase in diameter of the ball forming material as that material progresses 45 through the grooves of the dies.

Obviously, the dies may be double-sloped so as to form a ball at each stroke; and in Fig. 7 I show dies 1^a and 2^a so formed, indicating the die 1^a in two positions, one shown 50 in full lines and the other in dotted lines, which are positions corresponding to opposite limits of stroke of such dies. In the case of a mill constructed to roll balls in both directions of motion of the dies, such as 55 shown in Fig. 7, a ball blank will be dropped in between the dies at or near the beginning of each stroke of the dies.

In some cases, the stroke of the dies may be so great that it is inconvenient or uneconomical to reciprocate such dies by means of 60 hydraulic cylinders and pistons as shown in Figs. 1, 2 and 3. In such case I may use the alternative drive illustrated in Fig. 8, and comprising a gear wheel 21 mounted 65 upon the shaft 10 of the gear 9, and driven

by a pinion 22 mounted upon a shaft 23; which shaft 23 may be driven by a reversible steam engine, electric motor, or other suitable drive means.

The ball rolling mill shown in Figs. 1, 2 70 and 3, is provided with slide bearings for the die carriages. In some cases it is preferable to employ roller bearings for these die carriages, and such a construction I illustrate in Fig. 9, wherein the frame members 75 5^a and 6^a (corresponding to the frame members 5 and 6 of Fig. 1) are spaced away from the die carriages 3 and 4, a distance sufficient for the interposition of bearing rollers 24. These bearing rollers are preferably 80 connected by spacers 25 (in bearings of which spacers the axles of the rollers are mounted); whereby the rollers are kept at proper distances apart. The operation of this mill is obviously the same as the mill 85 shown in Figs. 1-3 inclusive.

In some cases it is desirable to mount the ball rolling dies for vertical reciprocation, instead of for horizontal reciprocation. Such a mill is illustrated in Fig. 10, the construction of the mill being substantially the same as that shown in Figs. 1, 2 and 3, except that the dies, the die carriages, and the frame members along which such die carriages move, are mounted vertically; also, 90 the hydraulic cylinders by which the dies are reciprocated. The vertical mill has the advantage that scale is not apt to collect in the guide ways of either die carriage, nor in the grooves of the dies. Also the vertical 100 mill occupies less floor space than does the horizontal mill.

In the form of machine shown in Fig. 9, wherein roller bearings are provided for the die-carriages, during the working strokes of 105 the dies the bearing rollers will, of course, move in the direction of motion of their respective dies, but through approximately half the range of travel of such dies. It is possible that, during the return stroke of 110 the dies, since there is then nothing between the dies, the bearing rollers for the upper die may be out of contact with the frame member 5^a in which case the upper bearing rollers would be carried back by the dies, 115 and, if nothing were provided to prevent, would be carried farther than they should be carried. To prevent this, I provide stops 26, (Fig. 11) engaging the spacers 25 when the bearing rollers near the proper limit of 120 their left hand movement; and I provide springs 27 engaging said stops 26, whereby the bearing rollers are brought to rest gradually.

Obviously, this machine is adapted for 125 forming articles of rotation other than balls. In Fig. 13 I show in transverse section dies, there designated by numerals 1^a and 2^a, having grooves adapted for forming objects of elliptical shape; and in Fig. 14 I show dies 130

designated by numerals 1^b and 2^b having grooves adapted for forming objects of another shape. In a broad sense, the objects formed by the dies shown in Figs. 13 and 14 5 may be called balls, and in the following claim I intend the term "ball rolling dies" and like terms to include dies for forming objects of rotation, of the general nature of balls, but not necessarily spherical.

10 It is sometimes desirable to provide the dies with separate and separately adjustable finishing dies. This is illustrated in Fig. 12, wherein numerals 1^c and 2^c designate the main ball forming dies, and numerals 28 and 15 29 designate separate and separately adjustable finishing dies. Such finishing dies, when employed, are generally set to give just that slight reduction to the material passing between them which is necessary in order 20 to insure rotation of the ball-bar 16 between them. It is easier to provide such separate finishing dies with ridges, between the grooves, adapted to sever or nearly sever the formed, or nearly formed, balls from one 25 another, than it is to provide the terminal portions of the main dies with ridges adapt-

ed to sever or nearly sever the balls one from another.

In my application for Letters Patent filed June 10, 1915, Sr. No. 33,223, I have illustrated, described and claimed, in connection with a somewhat different type of ball rolling mill, finishing dies, employed in connection with the main ball forming dies, as just above described. 30 35

What I claim is:

A rolling mill comprising in combination reciprocating die members, guides for said members, bearing rollers between one of said reciprocating members and its corresponding guide, a frame connecting said rollers, stop means for said frame, and means for communicating relative motion to said reciprocating member. 40

In testimony whereof I have signed this 45 specification in the presence of two subscribing witnesses.

FERDINAND E. CANDA.
